UNITED STATES PATENT OFFICE.

HENRY T. ORMONDE, OF LAKEWOOD, OHIO, ASSIGNOR OF ONE-HALF TO ORLAND F. BAUGHMAN AND ONE-FOURTH TO JULIUS ROEMER, BOTH OF LAKEWOOD, OHIO.

COMBINATION IGNITION LOCK.

Application filed March 30, 1922. Serial No. 548,006.

To all whom it may concern:

Be it known that I, HENRY T. ORMONDE, a citizen of the United States, residing at Lakewood, in the county of Cuyahoga and State of Ohio, have invented a certain new and useful Improvement in Combination Ignition Locks, of which the following is a full, clear, and exact description, reference being had to the accompanying drawings.

10 This invention relates to ignition locks for internal combustion engines, and has for its general object to provide for such engines a lock which, while comparatively simple of construction, will make it extremely difficult, 15 if not practically impossible, for other than

duly authorized persons to render operative the ignition circuits. The form shown herein is designed for engines using battery ignition systems and is a modification of my copending application executed simultaneously herewith, which discloses a lock of this same general character, but adapted for use with engines using magneto ignition.

In the drawings forming a part hereof, 25 Fig. 1 represents a sectional side elevation of a lock constructed in accordance with my invention; Fig. 2 a plan view of said lock; Figs. 3 and 4 sectional views corresponding

respectively to the lines 3—3 and 4—4 of Fig. 1; Fig. 5 a plan view of the intermediate combination switch plate; Fig. 6 a sectional detail on the line 6—6 of Fig. 3; Fig. 7 a detail in elevation and section showing one of the ignition circuit plugs in closed position; Figs. 8, 9 and 10, sectional details corresponding respectively to the lines 8—8, 9—9 and 10—10 of Figs. 4, 3 and 6, respectively; and Fig. 11 a diagrammatic view showing the electric circuits employed in the operation of the foregoing lock.

The lock to which this application is directed is a combination lock and, in the embodiment disclosed herein, includes a plurality of switch plugs; some of which correspond respectively to the spark plugs, and a plate cooperating with the said plugs to render the circuits to the spark plugs ineffective in the event that the plate is not set to a predetermined position and certain selected plugs are not also operated in conjunction therewith.

Describing the parts by reference characters, 1 denotes a casing, shown as cylindrical in outline and having at its lower end a plate 2 of insulating material and at its

upper end a flange 3 which is adapted to engage any suitable support, such as the rear face of the dash 4, the casing being clamped to the dash by means of said flange

60

and a cooperating clamping ring 5. The lock is mounted within the casing and comprises generally upper and lower heads 6 and 7 of insulating material and an intermediate metallic switch plate 8. The upper head is supported from the lower head by means of posts 9. Secured to and projecting through the central portion of the end lock 2 is a sleeve 10, through which extend the various wires for the ignition circuits.

70

The switch plate 8 is provided with a hub 8^a by which it is pinned to a vertical shaft 11, the pin being indicated at 12. Surrounding the hub 8^a is an insulation sleeve 13. The upper end of the shaft 11 projects above the head 6 and is there provided with a frusto-conical indicating member 14 having an indicating scale 15 thereon and provided at its extreme upper end with a knurled operating wheel or head 16. The scale upon the member 14 cooperates with an arrow 17 upon the top of the head 6 (see Fig. 2).

The plate 8 is provided with two concentric series of openings, there being an outer series of openings 18 and an inner series of openings 19. The particular embodiment of my invention shown herein is designed for use with a six-cylinder car; hence the numbers of the openings provided in the inner 90 details corresponding respectively to the and outer series are preferably multiples of lines 8—8, 9—9 and 10—10 of Figs. 4, 3 and 6, respectively; and Fig. 11 a diagrammatic view showing the electric circuits employed in the operation of the foregoing lock.

However, it will be understood that, for the purpose of my invention, no special number of openings in either series is essential. Adjacent to certain of the openings 18 and 19 of the switch plate 8 are movable plugs 21 mounted in insulating sleeves 21^a in the plate, each plug being normally retained in elevated position by means of a spring 22. In the embodiment of my invention shown herein, six such plugs 21 are shown, cooperating with six posts 21^b mounted in the base 7, the lock being designed for a six-cylinder engine. The purpose and mode of operation of these switch members will be pointed out hereinafter in

105

110

connection with the circuits.

The plate 8 is grounded at all times by a two-part terminal post comprising a lower section 25 having a plunger 26 slidably mounted in the upper part thereof pressed upwardly by a spring 27 so as to engage the peripheral portion of the plate 8. A wire 29 leads from the bottom of the post 27 to the frame or other ground, and the post 25 and the plunger are enclosed by an insulating sleeve 28 (Fig. 10).

Located within and adjacent to the periphery of the lower head 7 are posts 30 which are mounted in insulating sleeves 31 extending through the lower head 7 and into the bottom of the upper head 6 (see Fig. 9). Six such posts are shown, one for each of the spark plugs of a six-cylinder motor. Connected to the bottom of each post is a wire 32, and from the top of each post leads a wire 33. The posts 30 and the connections serve to conduct the current for the spark plugs to the appropriate switch plugs, mounted in the upper head, as will be explained hereinafter.

Also mounted in the lower head is a series of terminal posts 34, each having connected to the bottom thereof a wire 35 leading to a spark plug. The lock being designed for a six-cylinder motor, six such posts are indicated. Each post is mounted in an insulating sleeve 36 and is provided in its upper end with a socket 34^a. Four of the posts are shown as adapted to register with the openings 18, but the fifth and sixth are located within or toward the center of the head 7 from the other posts and each is adapted to register with an opening 19. The purpose of this arrangement will be explained hereinafter. The head 7 also carries short posts 39 (see Fig. 8), three such posts being shown. Two of these posts are so located as to register with the outer openings 18 in the plate 8 while the third is located so as to register with the inner openings 19 in said plate.

In the upper head 6 there are mounted the operating plugs by which the circuit from the battery to the primary winding of the coil is broken or closed and the spark plug circuits are opened or closed. These plugs, in conjunction with the wiring arrangement described and to be described herein, will close the circuit to all six of the spark plugs when the proper combination of plugs is selected, in conjunction with the proper positioning of the plate 8, but will prevent the closing or establishing of the spark-plug circuits under the other conditions. Generally speaking, two sets of plugs are shown as employed. The first set comprises six active plugs, each of which constitutes part of the circuit including a spark plug. Referring particularly to Fig. 6, 42 denotes one of the active switch plugs having at its upper end a knurled head 42^a and provided

with two longitudinally spaced grooves 42^b extending therearound and adapted to receive each a locking ball 43 pressed into engagement with the said plug by a spring 44. The springs and the balls for the various plugs are mounted in recesses in the head 6 which are closed by plugs 45.

The lower end of the body of each plug 42 is provided with a metallic flange 42^c and the lower end of each plug below such flange is reduced, as shown at 42^d, and is mounted in an insulation sleeve 46 having a socket 46^a in its lower end and adapted to receive the reduced upper extension of a sleeve 36 therebeneath and also having above such socket a shoulder 46^b which is adapted to engage the head 21^c of the plug 21 thereby to bring such post into electrical contact with the cooperating post 21^b in the head 7—see Figs. 6 and 7. In this embodiment of my invention six posts 21 are used and are so positioned that a post 21 will engage each post 21^b when the plate 8 is set in the proper position. The lower end of the reduced portion 42^d of each plug 42 constitutes a pin which is adapted to enter the socket 34^a in the top of the post 34 therebeneath, when the plate 8 is moved to bring the openings 18 into register with said plugs and posts. Surrounding each plug 42 above the flange 42^c is a metallic sleeve 47, said sleeve being mounted in the head 6 and having an extended base 47^a to which one of the conducting wires 38 is attached, whereby each of the plugs 42 may constitute part of the circuit including the wire 32, post 30, wire 33, post 34 and wire 35 leading to a spark plug. As shown more particularly in Fig. 3, four of the posts 42 are arranged to register with the openings 18 in the plate 8 while the other two are arranged to register with the openings 19 and thus to register with the cooperating posts 34.

There is also mounted in the head 6 a second set of plugs which are aligned with and arranged to cooperate with the posts 39, thereby to render the ignition or spark-plug circuits inoperative under conditions to be set forth hereinafter. One of these plugs is shown at 48 in Fig. 8 and is constructed similarly to the plugs 42, having a knurled head 48^a and locking grooves 48^b for the reception of a locking ball 43. The lower end of each plug 48 is provided with an enlargement 48^c adapted to contact with the side wall of the appropriate opening 18 or 19 and thereby with the plate 8. Tracing the circuits by reference to Fig. 11 it will be seen that the posts 21 are connected together in pairs by wires 50 and that four of the posts 21^b are connected together in pairs by wires 51. The current is brought from one terminal of the battery 52 by wire 53 to a terminal post 54 mounted in the head 7. From there it is taken by a wire 55 to

one of the posts 21^b. A wire 57 connects another one of the posts 21^b to a terminal post 59 in the head 7. A wire 60 leads from the other end of the terminal post 59 to one terminal 61 of the primary winding of the coil, indicated generally at 62, and a wire 63 leads from the other terminal 64 of such winding to the condenser and breaker points, indicated generally at 65, 10 said breaker points being grounded to the frame by a wire 66. A wire 67 has one end connected to the terminal 68 of the secondary winding and the other end grounded in the frame, while a wire 69 connects the 15 other terminal 70 of the secondary winding to the distributor arm 71 which is adapted to successively engage the contacts 72 carried by the distributor plate 73. Each wire 32 has one end connected to a contact 72 20 and the other end to the sleeve 47 surrounding the plug 42 in the upper head 6. As has been explained hereinbefore, this combination of wires 32 with the plugs 42 is secured by connecting each wire with the post 25 30 and leading a wire 33 from each of said posts to the flange 47^a of the sleeve 47. Connections from the posts 42 through the posts 34 to the spark plugs are made by the wires 35, the spark plugs being indicated conventionally at 74 and the engine 35 ground being indicated at 74^a. The posts 39 are electrically connected to the post 54 by wires 75. In order to supply current to the spark plugs it is first necessary to electrically connect the terminal post 54 with the terminal post 59 to close the circuit from the battery to the primary winding of the coil. This is done by rotating the knob 16 to the proper position, which will in turn 40 so position the plate 8 that all of the plugs 21 are directly above the posts 21^b. The plugs 42 are then pressed inwardly, which will bring the plugs 21 into contact with the posts 21^b, and this will allow the current to pass from the terminal post 54 through the wire 55 to one of the posts 21^b, indicated at 56 in Fig. 11, and thence to the contacting plug 21, through the wires 50 and 51 and connected plugs 21 and posts 50 55 to the post indicated at 21^{bx} in Fig. 11 and from there through the wire 57 to the terminal post 59 and thence through the wire 60 to the primary winding of the coil and through the condenser and breakers 65 and to the ground through the wire 66 and back to the battery through the battery ground wire 80.

If, however, one of the plugs 48 is inserted it will come in contact with a post 60 39 and then the current will flow from the terminal post 54 through a wire 75 to such post 39, thence to the plug 48 and to the plate 8 and from there through the plunger 26, post 25 and wire 29 to the ground, it 65 being understood that an electric current

will always follow the line of least resistance.

It will be seen that, by the construction and arrangement of the parts disclosed herein, in order that current may flow 70 through the primary winding from the battery, it is necessary that all of the plugs 21 shall be brought into register with all of the posts 21^b and that all of the plugs and posts shall be brought into contact through 75 the movement of the plugs 42. Should one or more of the plugs 48 register with openings 18 having the plugs 21 adjacent thereto with posts 21^b beneath such plugs, then the 80 operation of the plugs 48 will be ineffective, since the distance between the grooves 48^b will prevent the locking of the plugs in their depressed condition. Should, however, any of the plugs 48 register with a post 39, then the 85 operation of such plug would immediately ground the circuit including the primary winding. In brief, in order to render the ignition system operative, the plugs 21 must be brought each into operative relation to a post 21^b and to a plug 42—otherwise the circuit including the primary winding cannot be closed. Furthermore, none of the plugs 38 must be pushed inwardly into contact with a post 39, or the circuit including 90 the primary winding will be grounded. 95 The parts being enclosed within the casing 1, the proper arrangement of the plugs 42 and 21 can be determined only by knowing the combination; and the difficulty of ascertaining this combination may be enhanced by multiplying the number of grounding plugs 48 and by suitably varying the positions of said plugs and of the plugs 42 and 21.

For convenience of reference, the term 105 "primary winding" will be employed in the claims as including not merely the winding, but the necessary breaker points and condenser to induce in the secondary winding the kind of current essential to the proper 110 operation of the spark plugs.

Having thus described my invention, what I claim is:

1. The combination, with the spark plugs of a multi-cylinder internal combustion engine, a source of electrical energy, a primary winding and a secondary winding, a circuit including the said source and the primary winding, and a circuit including 115 the secondary winding and the spark plugs in succession, of a lock comprising a plurality of switch posts, a movable plate, switch plugs carried by said plate and movable toward and from said posts, said plugs and posts being in the first mentioned circuit, a 120 second series of switch posts corresponding in number to the spark plugs, switch plugs movable toward and from said posts and each adapted to engage one of the first mentioned plugs thereby to move it into 125 130

contact with its post, and a plurality of switch plugs resembling the second mentioned switch plugs and each adapted when moved to ground the primary circuit.

- 5 2. The combination, with the spark plugs of a multi-cylinder internal combustion engine, a source of electrical energy, a primary winding and a secondary winding, a circuit including the said source and the 10 primary winding, and a circuit including the secondary winding and the spark plugs in succession, of a lock comprising a plurality of switch posts, a movable plate, switch plugs carried by said plate and movable toward and from said posts, said plugs and posts being in the first mentioned circuit, a second series of switch posts corresponding in number to the spark plugs, switch plugs movable toward and from said 15 posts and each adapted to engage one of the first mentioned plugs thereby to move it into contact with its post, and one or more additional switch members arranged to ground the primary circuit.
- 20 3. The combination, with the spark plugs of a multi-cylinder internal combustion engine, a source of electrical energy, a primary winding and a secondary winding, a circuit including the said source and the 25 primary winding, and a circuit including the secondary winding and the spark plugs in succession, of a lock comprising a plurality of movable switch members in series with the first circuit, and a plurality of 30 movable switch members in the second circuit.
- 35 4. The combination, with the spark plugs of a multi-cylinder internal combustion engine, a source of electrical energy, a primary winding and a secondary winding, a circuit including the said source and the 40 primary winding, and a circuit including the secondary winding and the spark plugs in succession, of a lock comprising a plurality of movable switch members in series with the first circuit, and a plurality of 45 movable switch members in the second circuit and each arranged, when moved in a direction to close its spark-plug circuit, to engage one of the first mentioned switch 50 members and move the same in a direction to close the first circuit.
- 55 5. The combination, with the spark plugs of a multi-cylinder internal combustion engine, a source of electrical energy, a primary winding and a secondary winding, a circuit including the said source and the primary winding, and a circuit including the secondary winding and the spark plugs in 60 succession, of a lock comprising a plurality of movable switch members in series with the first circuit, a plurality of movable switch members in the second circuit and each arranged when moved in a direction to close its spark plug circuit, to engage one of the first 65 spark plug circuit, to engage one of the first

mentioned switch members and move the same in a direction to close the first circuit, one or more additional movable switch members, and means including each of the last mentioned members for grounding one of the 70 aforesaid circuits.

6. The combination, with the spark plugs of a multi-cylinder internal combustion engine, a source of electrical energy, a primary winding and a secondary winding, a circuit including the said source and the primary winding, and a circuit including the secondary winding and the spark plugs in succession, of a lock comprising a plurality of movable switch members in series 80 with the first circuit, a plurality of movable switch members in the second circuit and each arranged, when moved in a direction to close its spark plug circuit, to engage one of the first mentioned switch members and move the same in a direction to close the first circuit, one or more additional movable switch members each resembling the second members, and means including each of the last mentioned members for 85 grounding the first circuit.

7. The combination, with the spark plugs of a multi-cylinder internal combustion engine, a source of electrical energy, a primary winding and a secondary winding, a circuit including the said source and the primary winding, and a circuit including the secondary winding and the spark plugs in succession, of a combination lock comprising a plurality of movable switch members in series with the first circuit, a plurality of movable switch members in the second circuit and corresponding in number to the spark plugs, and one or more additional 95 switch members arranged to ground the primary circuit.

8. The combination, with the spark plugs of a multi-cylinder combustion engine, a source of electrical energy, a primary winding and a secondary winding, a circuit including the said source and the primary winding; and a circuit including the secondary winding and the spark plugs in succession, of a lock comprising a series of movable switch members in series with the first circuit, a series of movable switch members in the second circuit and each adapted, when moved in a direction to close its circuit, to move one of the first mentioned switch members in a circuit-closing direction, means for moving one series of such switch members with reference to the other series of such switch members whereby the first mentioned members may be operated by different members of the second series of members, and means including one or more switch members resembling those of the second set for 110 grounding the primary circuit.

9. The combination, with the spark plugs of a multi-cylinder internal combustion en- 115

- gine, a source of electrical energy, a primary winding and a secondary winding, a circuit including the said source and the primary winding, and a circuit including the secondary winding and the spark plugs in succession, of a lock comprising a base carrying a plurality of switch members corresponding in number to the spark plugs, a plate movable with respect to said base, a plurality of switch plugs carried by said plate and adapted to cooperate with the said switch members, the said plugs and members being in series with the primary circuit, a plurality of switch members also carried by said base and corresponding in number to the number of said plugs, the said plate having openings therethrough in excess of the number of said plugs for the passage of said switch plugs and each of the last mentioned switch plugs being adapted by its circuit-closing movement to engage one of the first mentioned switch plugs thereby to close the circuit including the same, each of the second mentioned switch plugs being included in a spark plug circuit, and one or more additional switch plugs, resembling the second mentioned switch plugs in appearance, and means including each of the last mentioned switch plugs for grounding the primary circuit.
10. An ignition lock for the spark plugs of a multi-cylinder internal combustion engine comprising a source of electric current, a primary winding, a secondary winding, a distributor in the circuit including the secondary winding and the spark plugs, a plurality of switch members controlling said circuit, the said switch members corresponding in number to the number of said spark plugs, and a plurality of similar switch members arranged in proximity to the first mentioned switch member and each arranged, when operated, to ground or render inoperative the circuit including the primary winding.
11. An ignition lock for the spark plugs of a multi-cylinder internal combustion engine comprising a source of electric current, a primary winding, a secondary winding, a movable plate having openings therethrough in excess of the number of the said spark plugs, switch plugs each adapted to be moved through said openings to close the circuit from the secondary winding including the said spark plugs, switch plugs in series with a circuit including the primary winding and each adapted to be moved to circuit-closing position by the movement of the first mentioned switch plugs through the openings in said plate.
12. An ignition lock for a multi-cylinder internal combustion engine comprising a base carrying a plurality of switch members corresponding in number to the number of cylinders and the spark plugs therefor, a source of electric energy, a primary winding, a circuit from said source to said winding and including the aforesaid switch members, a plate movable with respect to said base, a plurality of switch plugs carried by said plate and adapted to cooperate with said switch members to close said circuit, the said plate having a plurality of openings therethrough in excess of the number of the said plugs and members, a plurality of switch members also carried by said base and corresponding in number to the number of said cylinders and plugs, a plurality of switch plugs movable through said openings to cooperate with the last mentioned members thereby to close a circuit including the secondary winding and the spark plugs, additional plugs also movable through the openings in said plate and each adapted to close a ground circuit from the source of energy to the primary winding.

In testimony whereof, I hereunto affix my signature.

HENRY T. ORMONDE.
